WILLIAM H. TAYLOR, OF PROVIDENCE, RHODE ISLAND.

PIVOT-MOUNTING FOR PINS OF BROOCHES AND THE LIKE.

1,304,406.

Specification of Letters Patent. Patented May 20, 1919.

Application filed February 21, 1918. Serial No. 218,553.

To all whom it may concern:

Be it known that I, WILLIAM H. TAYLOR, a citizen of the United States, residing at Providence, in the county of Providence and State of Rhode Island, have invented a new and useful Pivot-Mounting for Pins of Brooches and the like, of which the following is a specification.

This invention has reference to pivoted mountings for pins of brooches and the like, and its object is to provide a form of cup or housing for the pivoted or hinged end of the pin which permits its manufacture of thin stock without liability of loosening the parts in use.

In accordance with the invention, the cup or housing is such that it may be drawn in one piece from the stock employed, with one part of the housing movable with relation to the other parts to permit the location of the hinge or pivot end of the pin in the cup or housing, and then by properly closing the movable part, firmly lock the pin in the housing, with a freedom of movement, when employed in a breast pin or brooch, permitting the fastening or unfastening of the pin in the usual manner.

The invention will be best understood from a consideration of the following detailed description, taken in connection with the accompanying drawing forming part of this specification, with the further understanding that, while the drawing shows a practical form of the invention, the latter is not confined to any strict conformity with the showing of the drawing but may be changed and modified so long as such changes and modifications come within the scope of the appended claims.

40 In the drawing:

Figure 1 is a perspective view of the housing showing the small portion of the bar to which the housing is secured, and also a portion of the pin shank in the open position;

Fig. 2 is a longitudinal section of the housing shown in Fig. 1;

Fig. 3 is a section on the line 3—3 of Fig. 2;

50 Figs. 4 to 8 are perspective views of housings differing in some particulars from that shown in Fig. 1, and also differing in some particulars from each other.

55 Referring to the drawing, and particularly to Figs. 1, 2 and 3, there is shown a

housing 1 which in Fig. 1 is mounted on a bar 2, the latter being indicative of any suitable bar such as is used in a breast pin or brooch. It is customary to make the housing 1 separate from the bar, and subsequently 60 solder it thereto.

The housing comprises side members 3, top and bottom members 4 and 5 respectively, and end members which in Figs. 1, 2 and 3 are indicated at 6 and 7 respectively. 65 At one end, the housing is provided with an opening 8, and this opening has a continuation 9 into the corresponding end of the top 4. The interior of the housing is of a height, breadth and thickness to snugly yet freely 70 contain an eye 10 at one end of a shank 11, which latter may be taken as indicative of the usual fastening pin for holding the bar 2 in place. The eye 10 of the pin 11 is shown as a flat circular eye, so that by engaging the top and bottom portions 4 and 5 and the end portions 6 and 7, the pin 11 may be turned about the axis of the eye 10 as upon a pivot, and is prevented from lateral movement by the two sides 3. 75

The housing is a one-piece structure which may be drawn from stock of very thin gage, say, about fourteen one-thousandths of an inch thick, the housing itself being from one-eighth of an inch to three-sixteenths of an 80 inch in diameter.

The side walls of the housing are integrally joined at the top and bottom and one end or at the bottom and both ends, thus producing a receptacle for the eye end of 90 the pin which is particularly resistant to distorting forces. One end of the housing or the top thereof is bendable to expose the interior of the housing to a sufficient extent to introduce the eye end of the point, after 95 which the bendable portion is moved against the sides of the housing to confine the eye or pivot end of the pin within the housing against accidental escape therefrom.

In Fig. 1 and associated figures, the end 7 100 is in the form of a flap constituting the bendable portion of the housing and also is shorter than the height of the housing with its upper end constituting a shoulder against which the pin 11 may be brought into engagement before the free end of the pin is locked by the customary latch, thus putting the pin under a desirable strain to hold it in the latch. The tendency of such strain is to bring the eye 10 into pressing engagement 110

with the top 4, but in Fig. 1 and associated figures, the top 4 is an integral bridge piece connecting the two side members 3, wherefore the top 4, even though of very thin stock, is effectively resistant to the strains to which it is subjected. Moreover, the integral top or bridge piece 4 and the integral bottom piece 5, as well as the integral end 6, effectively resist any side strains brought 10 upon the housing by forces exerted sidewise upon the pin 11.

In Fig. 4, the structure is the same as in Figs. 1, 2 and 3 except that the end 7 is replaced by an end 7^a movable toward and 15 from the body of the housing about a connection to one of the side members 3 instead of about a connection to the bottom member 5 as in the preceding figures. In Fig. 1, that extremity of the end member or flap 7 forming a shoulder indicated at 12 is replaced in Fig. 4 by an end notch 12^a, into which the pin 11 may seat when in the locked position.

In the structure shown in Fig. 5, an integral end member 7^b replaces parts 7 or 7^a of Figs. 1 and 4, and the end member 6 is replaced by a flap 6^a which may be bent to provide an entrance for the eye 10 of the pin and then bent back into place to hold the eye of the pin within the housing.

30 In Fig. 5, the flap 6^a is bendable about an integral connection with the top 4 of the housing. In Fig. 6, the arrangement is the same as in Fig. 5 except that the flap 6^a is replaced by a flap 6^b bendable about a connection with one of the sides 3.

In the form shown in Fig. 7, the top 4 is replaced by a flap 4^a having a bendable connection with the end 6, and in Fig. 8, there is a flap 4^b having a bendable connection 40 with one of the sides 3.

In all the forms shown, which may be taken as indicative of still other forms of like nature, the housing has a narrow portion representing either an end or a top 45 integrally connected to the bottom or the top or one side of the housing, and bendable to provide an entrance to the housing large enough to admit the eye end of the pin with the sides of the housing fixedly related one 50 to the other at all times and spaced by a distance to snugly yet freely receive the eye end of the pin between them, so that such eye end is embraced flatwise by the permanently joined sides.

55 In each instance, the flap is no larger than is needed, to give entrance of the eye of the pin to the housing, and the flap is so located and joined to the housing that no strains to which the pin is subjected in use 60 will move the flap toward the open position, even though the flap itself is merely bent against the remainder of the housing and in nowise specially fastened thereto.

In each form, the sides of the housing are 65 permanently held together along the major

part of their margins, and hence effectively resist side strains, permitting the whole housing to be made of very thin stock. This is advantageous when relatively soft or pliable metals are used, permitting the housing 70 when made of an expensive metal like gold to be produced cheaply, because of the small amount of metal needed. If the sides and other parts of the housing be made of heavy enough stock, they will resist side and other 75 strains, even though the housing be bent up into shape without the parts being permanently united, but in such event, the device is either too bulky, or in the case of costly metals, is too expensive to be commercially 80 successful in competition with equally effective but lighter devices.

While the housing is shown as of rectangular contour, it is quite feasible to round it more or less to avoid sharp corners, 85 and it is to be understood that the invention covers other than strictly rectangular housings.

What is claimed is:

1. In jewelry, a housing for inclosing a 90 flat circular eye at one end of a pin, comprising parallel side members and marginal members, one of which constitutes a lid for an opening through which the head of the pin is introduced into the housing, and the 95 other marginal members integrally coupling the side members throughout the major portion of the margin of the housing, whereby the rigidity of the housing is sufficient to permit its formation from thin stock without liability of the housing spreading and permitting the escape of the eye of the pin.

2. In jewelry, a housing for inclosing a flat circular eye at one end of a pin, comprising parallel side members and top, bottom and end marginal members with one of the marginal members constituting a lid for an opening between the side members through which the head of the pin is introduced into the housing, and the other marginal members integrally coupling the side members and together forming the major 110 part of the marginal portion of the housing.

3. In jewelry, a housing for pivotally mounting a pin with a flat circular eye at 115 one end, comprising side members spaced apart to closely embrace the sides of the eye of the pin, and a top, a bottom and one end portion integrally coupling the corresponding portions of the side members, and a flap 120 at the other end of the housing fast to one side member and constituting a lid for the corresponding marginal portion of the housing to permit the introduction of the eye end of the pin into the housing.

4. In jewelry, a housing for inclosing a flat circular eye on one end of a pin, comprising parallel side members spaced to closely embrace the sides of the eye of the pin, and top, bottom and end members 130

closely embracing the circumferential portions of the eye of the pin, with the top, bottom and one end member of the housing integral with both side members and the 5 other end member constituting a flap of less length than the corresponding end of the housing and forming a lid movable to admit the eye of the pin into the housing, and also movable against the side members to then 10 hold the eye of the pin in the housing, the

flap constituting a shoulder forming a stop for the pin.

In testimony, that I claim the foregoing as my own I have hereto affixed my signature in the presence of two witnesses.

WILLIAM H. TAYLOR. [L.S.]
